CLAIM

The ornamental design for a triangular urinal floor mat, as shown and described.

DESCRIPTION

FIG. 1 is a perspective view of a triangular urinal floor mat showing my new design;

FIG. 2 is a top plan view thereof;

FIG. 3 is a bottom plan view thereof;

FIG. 4 is an elevational right-side view thereof;

FIG. 5 is an elevational left-side view thereof;

FIG. 6 is an elevational front-side view thereof; and,

FIG. 7 is an elevational rear-side view thereof.
